UNITED STATES PATENT OFFICE.

MAHLON A. SIDWELL, OF LOS ANGELES, CALIFORNIA.

STUFFING AND PACKING MACHINE.

1,294,104.

Specification of Letters Patent. Patented Feb. 11, 1919.

Application filed April 30, 1918. Serial No. 231,614.

To all whom it may concern:

Be it known that I, MAHLON A. SIDWELL, a citizen of the United States, residing at Los Angeles, in the county of Los Angeles 5 and State of California, have invented a new and Improved Stuffing and Packing Machine, of which the following is a specification.

This invention has reference to improvements in stuffing and packing machines more especially designed for stuffing and packing dolls, toy animals, pin cushions and other similar articles and primarily the invention has for its object to provide an improved machine of the general character 15 stated, of a simple, compact and economical construction in which the parts are co-operatively arranged for effecting a great saving in the labor usually expended in stuffing and 20 packing the material to produce the articles stated.

Another object of my invention is to provide an improved stuffing and packing machine of that type in which the material is 25 constantly supplied from a hopper to the packing element, having specially constructed means for agitating the material to overcome clogging and bridging, whereby to maintain a constant and uniform feed 30 thereof to the said packing element.

With other objects in view that will hereinafter appear, my invention embodies, in a machine of the character mentioned, certain improved features of construction and novel 35 arrangement of parts, all of which will be first explained in detail, then specifically pointed out in the appended claims and illustrated in the accompanying drawings, in which:

40 Figure 1 is a side elevation of a packing and stuffing machine embodying my invention.

Fig. 2 is a plan view thereof, the main hopper being shown broken away.

45 Fig. 3 is a vertical longitudinal section of my machine taken substantially on the line 3-3 on Fig. 2.

Fig. 4 is a perspective view of the agitator devices for keeping the packing material 50 in the main or feeding hopper in motion.

Fig. 5 is a front elevation of the plunger device and the crank disk that connects therewith.

Fig. 6 is a perspective view of the con-

veyer funnel and the filler attachment connected therewith. 55

Fig. 7 is a detail perspective view of the mechanism by which the down flow of the packing material is regulated.

Fig. 8 illustrates a number of different 60 shapes of wooden tips.

Briefly my invention comprises a rammer or packer which is adapted to pack the filling material into the body or form held in position for receiving the packing, the said 65 packer being so combined with a filler tube and means for constantly feeding the material by gravity to the filler tube and a motor driven reciprocating plunger to which the rammer or packer element is attached and 70 which carries devices for constantly agitating the packing material in its flow from the main feed hopper to the filler tube, whereby to maintain such uniform feed of the material to the filler and packer devices 75 that the stuffing material that comes through the filler is packed hard and evenly throughout the entire length of the body to be filled, the said packing element being operated under high speed to thereby render the machine one of great efficiency and a time 80 saver.

In the drawings, I have illustrated a practical and preferred arrangement of my invention, it being, however, understood that 85 the said arrangement is susceptible of various changes in form, proportion, and the detail combinations of the parts may be changed without departing from the principle of my invention as comes within the 90 scope of the appended claims.

In carrying out my invention, the operative parts are mounted on a wooden base or supporting frame, in practice about 18 inches in height and of like width and which 95 includes a table or bed portion 1, opposite sides 10 and a bottom 11.

2 designates, what is hereinafter termed, the packer funnel and it is detachably and pendently sustained on the bottom of the 100 bed 1 by a number of (preferably three) clips 3-3 that are attached to the bed 1 by the nut and bolt connections 30-30, as shown.

Funnel 2 includes a pendent straight neck 105 20 that is provided with a laterally projected screw stud 21, the purpose of which will presently appear.

4 denotes a filler tube that is tapering from the upper to the lower or discharging end 40 and the upper end 41 of the said tube, which is of uniform diameter throughout, has a bayonet slot 42 for interlockably engaging with the screw stud 21 on the funnel neck 20, when the several parts are assembled for use.

10 A metal cap or casting 5 that has a base rim 50 is secured on top of the table 1 by clamp screws 51—51, as shown.

15 6 designates a plunger rod that passes through a central aperture 12 in the table 1 with its lower portion extended downwardly into the packer funnel 2 and the filler tube 4. The lower end of the rod 6 terminates in a threaded socket 60 for receiving the threaded ends of packer tips 61, preferably of wood, and which, when applied to the plunger, are held from working loose by jam nuts 62, as shown.

20 The packer tips may be of varied design according to the particular character of the material to be worked, a number of said 25 designs being indicated by Fig. 8.

25 In practice in a machine such as shown, the stroke of the plunger rod is $1\frac{1}{4}$ inches and the said plunger rod is so mounted, relatively to the discharging end of the filler 30 tube 4, that the tamping end of the packer tip comes about $\frac{1}{16}$ of an inch below the said filler tube bottom.

35 The plunger 6 is operated at a high speed, in practice about one thousand strokes per minute, by motor transmission which may be arranged as is best shown in Fig. 3, from which it will be noticed a cast metal framing is mounted at one end on the table or bed 1 and at the other end on the cap 5 and 40 the said framing includes a hollow standard 7 that merges with a horizontal arm 70, the inner open end of which joins with a standard having a chamber formed by an inner vertical portion 71, a top plate 72 and a 45 slide 73 which constitutes the front of the said chamber and which may be readily raised for giving access to the said chamber for adjusting the crank connections that join with the plunger rod 6, whose upper 50 end is guided and works through an aperture 74 in the top plate 72.

55 A drive shaft 8 is journaled in bearings 80—81 at the opposite ends of the hollow arm 70, one end of which extends beyond the arm 70 and carries a pulley wheel 82 around which passes a belt drive 83, as shown.

60 The other end of the shaft 8 carries a crank disk 84 with which connects one end 65 of a link 9 whose other end flexibly connects with a clamp 90 attached to the plunger rod 6, the said connection being such that reciprocable motion is imparted to the plunger 6, when the shaft 8 is motor or manually rotated.

14 designates a chute whose lower end is supported in an aperture 13 in the bed 1 and, the said chute, discharges into the packer funnel 4. The chute 14 is supported in the cap plate or casting 5.

15 designates a slide member that is guided in the cap plate and takes across the chute 14 for regulating the flow of the material to the packer funnel.

16 denotes a main or feed hopper, in practice suitably suspended at the upper end with its lower or discharging end projected into the tube 14.

20 In packing machines of the general character stated and in which hopper devices are employed for leading the material, by gravity, to the filling and packing elements, more or less difficulty is found for maintaining a uniform and constant gravitation of the material to the discharging end of the 25 hoppers and to overcome such conditions agitator devices of more or less efficiency have heretofore been employed to provide for a desired continuous movement of the material.

25 In my construction of packing and stuffing machine, I have provided a simple and effective means for constantly agitating the material and keeping it from bridging over the discharging outlets, and the said means 30 includes a center rod 17 that extends up through the main hopper 16 and whose lower end is bent at a slight angle, as at 17^a, and terminates in a right angled extension 17^b that is attached to the plunger rod 6, 35 as is best shown in Fig. 4.

40 A bent portion 17^a of the rod 17 is guided in an elongated slot 15^a in the cut-off or slide member 15 that is illustrated in detail in Fig. 7.

45 As is best shown in Fig. 3 of the drawings, the center rod 17, which extends nearly to the top of the hopper 16, carries a pair of oppositely projected sets of agitator fingers 18—18, each of which is formed of a 50 wire that is passed through the rod 17 and has its opposite ends bent at right angles to form agitator fingers, the fingers of the upper agitator being bent downwardly toward the upwardly bent fingers of the lower 55 agitator member.

60 An agitator finger 25, preferably a flexible rod, is attached to the center bar and the said rod 25 is guided through an elongated slot 15^b in the cut-off slide 15 and the 65 said rod passes down through the guide funnel 4 and into the filler tube. Other flexible rods 26—26 are attached to the plunger rod 6 and they also extend through the funnel 4 and down into the filler tube, as 70 shown.

75 From the foregoing description taken in connection with the drawings, the complete construction, the manner of its operation and the advantages of my invention will be 80

readily apparent to those skilled in the art to which it appertains.

The manner in which my machine is used is as follows: The article to be stuffed and packed is held with the lower end of the filler tube through an opening left in the said article for the purpose.

The stuffing material which gravitates from the main hopper passes down through the guide receptacle or funnel, from which it flows into the filler hopper and into the filler tube.

Power being applied to the driven shaft 8, rapid motion is imparted to the plunger and since the center rod with the agitator devices are caused to reciprocate with the said plunger, the material in the main hopper, the guide funnel and the filler hopper is kept in constant agitation as it gravitates toward the filler tube discharge, it being understood that additional shaking up of the material in the filler hopper and the filler tube is provided for by the wires attached to the plunger, as before stated.

25 As the article being packed becomes gradually filled, the operator by proper manipulation can so hold the article, relatively to the discharge end of the filler tube, until the body has been fully stuffed and packed.

30 What I claim is:

1. In a filling and packing machine, the combination with a filler tube, a feed hopper in communication with the said tube and from which the material is delivered into the tube; of a plunger or rammer, means for reciprocating the plunger or rammer and other means movable with the said plunger or rammer for constantly agitating the material in the hopper and the filler tube.

40 2. In a filling and packing machine, a suitable support including a table portion, a filler and packing means pendently supported from the bottom of the table, the said means including a filler tube adapted for being projected into the body to be filled and packed, a funnel connected with the filler tube, a main material receiving hopper from which the packing material gravitates into the filler funnel, a material

50 agitator within the main hopper, a combined packer and plunger operably mounted in the filler tube and funnel, power transmission for imparting reciprocable motion to the said plunger and packer, the said agitating devices including a center rod connected to and movable with the plunger and packer.

55 3. In a filling and packing machine, a

suitable support including a table portion, a filler and packing means pendently supported from the bottom of the table, the said means including a filler tube adapted for being projected into the body to be filled and packed, a funnel connected with the filler tube, a main material receiving 60 hopper from which the packing material gravitates into the filler funnel, a material agitator within the main hopper, a combined packer and plunger operably mounted in the filler tube and funnel, power transmission for imparting reciprocable motion to the said plunger and packer, the said agitating devices including a center rod connected to and movable with the plunger and packer, and flexible wire agitators 65 connected with the plunger and packer and movable through the packer and filler and in the main hopper.

4. In a filling and packing machine, a supporting frame including a tube, a filler 80 and packing means pendent from the table, the said means including a funnel, a filler tube suspended from the funnel, the casting mounted on the table, a main funnel and a conveyer supported on top of the table 85 to one side of the vertical axis of the filler and packing means, the said conveyer having its discharge end projected through the table and into the funnel beneath it, a vertical reciprocable plunger rod operable within the said funnel and the filler tube, drive mechanism mounted on the casting connected with and adapted to impart reciprocable motion to the plunger rod and agitator devices within the funnel, the filler 90 tube, the main hopper and the conveyer, the said devices being connected and movable with the plunger rod.

5. In a filling and packing machine, a downwardly tapering filler tube and means 100 tending to constantly feed the filling material into the said tube; of a plunger and rammer vertically reciprocable in the filler tube and including a ramming tip whose packing end is of a diameter substantially 105 that of the discharging end of the filler and means for imparting such reciprocable motion to the plunger, whereby at the limit of the down or packing stroke, the packing end of the rammer is slightly projected below the discharge end of the filler tube and adapted to substantially close the flow of the material through the said discharge end.

MAHLON A. SIDWELL.
